UNITED STATES PATENT OFFICE.

STORY B. LADD, OF WASHINGTON, DISTRICT OF COLUMBIA.

AERONAUTIC CHART.

Application filed March 6, 1922. Serial No. 541,549.

To all whom it may concern:

Be it known that I, STORY B. LADD, a citizen of the United States, residing at Washington, in the District of Columbia, have 5 invented certain new and useful Improvements in Aeronautic Charts, of which the following is a specification.

This invention relates to an aeronautic chart system adapted to function in aiding 10 the aviator or observer to lay his course direct for the objective point, also to make it possible for him, enroute, to check and correct his course for air-drift.

The underlying principle of the invention 15 or chart is the subdivision of the continental areas into blocks, and the installation of markers at the intersection of block lines which, by reason of their shape, contour, or distinguishing features, as viewed from the 20 aeroplane, or overhead, will indicate to the aviator or observer the geographic position of the marker.

It is not proposed to post the entire country, nor any portion thereof, by the installation 25 of markers at all points, but to provide a system which can be added to or differentiated as the growth of air-travel requires, and whenever or wherever a marker is installed, whether under national or 30 State auspices, by aero-clubs, chambers of commerce, or other organization, it will be in harmony with the general plan, and become a part of the continental system.

The blocks will be spherical quadrilaterals, 35 laid out on lines of latitude and longitude, the term as here used referring to an area bounded on the east and west by north and south lines, and on the north and south by east and west lines; by meridians of longitude and parallels of latitude, respectively.

The term "marker" as used herein refers 40 to a device or structure, preferably erected so as to stand above other objects in the neighborhood and be distinguishable at a distance.

It is important that the system, in its 45 growth and development, be continental in its scope, without breaks at national or State boundaries, and that the character or indicia of all markers, wherever installed, shall be alike in markings and significance, and suggestive of the same import to the aviator. In this presentation it is described as applicable to a world system.

50 Eight degrees of longitude and latitude represent a major block, these being sub-

divided into quarter sections, and each quarter section into quarter blocks, giving, as a result, 16 quadrilaterals, 2° by 2° , these being referred to as intermediate blocks. 60 These intermediate blocks are in like manner subdivided into quadrilaterals of $24'$ by $24'$, making 25 subdivisions. These are the minor-block units, and each marker that is installed represents a minor-block. 65

Each major block being of 8° standard for all countries, those of the equatorial belt will be approximately 550 miles square with intermediates ($2^\circ \times 2^\circ$) of 138 miles square, and minor blocks ($24' \times 24'$) of 27.6 70 miles. Going north and south from the equator, the distances along meridional lines will be constant, with the distances along parallels of latitude gradually diminishing. At the 40th parallel, the east and west 75 dimensions for the major blocks will be approximately 428 miles; for intermediates, 107 miles; and for a minor block, 21.4 miles. At the 50th parallel of latitude, these distances will be approximately 360 miles; 90 80 miles; and 18 miles, respectively; and at 60° , 280 miles, 70 miles, and 14 miles respectively.

Fig. 1 is a diagrammatic view showing 85 a section of continental area divided into blocks in accordance with the present invention;

Fig. 2 is an enlarged diagrammatic view illustrating division into minor blocks; and

Fig. 3 is a perspective view showing a 90 marker embodying the present invention; and

Fig. 4 is a series of top plan views of markers embodying the present invention.

For purposes of identification, the intermediate blocks are lettered A to P, beginning 95 at the northwest corner of a major block and in quarter section groups, the letters A, B, C, and D, as in diagram Figure 1, indicating the four intermediate blocks of 100 the northwest quarter section; E, F, G, and H, those of the northeast quarter section; I, J, K, and L, the southwest quarter section; and M, N, O, and P, the southeast.

The major blocks are designated by the 105 longitude and latitude of the northwest corner of the block, and as all major blocks are 8° in dimensions these numbers are always multiples of 8. Thus "104-48" defines or identifies a block bounded by 110 meridians 98° and 104° (in the western hemisphere) and by parallels of latitude 40° .

and 48° (in the northern hemisphere); and "104-32" identifies the major block covering southern Texas and a portion of Mexico. If there be any question as to the quarter of the globe, suggestive indicia to that effect is associated with the reference or designating numbers. In this event, the above noted blocks will be designated as "N. W. 104-48" and "N. W. 104-32" "N. E. 40-48" is a block covering parts of southern Russia and the Caucasus; and "S. E. 16-24" (still using the northwest corner for blocks in the southern hemisphere), the South African Union; and "S. W. 64-32" portions of Argentina and Uruguay.

The letter designation of the intermediate block follows the major block designation—thus "N. W. 104-48c" indicates the intermediate block C in a major block, the northwest corner of which is 104° west longitude, and 48° north latitude.

The minor blocks are designated 1 to 25 beginning at the northwest corner of the intermediate block. In designating a minor block, the number follows the intermediate block letter, thus, "104-48C10" identifies a specific location of a minor block (which may or may not have been installed), in block "104-48C."

The markers are platform structures, as indicated in the diagrammatic Figures 3 and 4, carried by skeleton towers, high enough to clear or be observable above surrounding objects, and, in forest and timbered districts, to show above the trees; and in open country they may be of an elevation sufficient to be out of the way of cattle and drifting snows.

In mountainous or broken country where the true location of a marker comes in a gorge, or where it would not be visible from a distance, it will be located at the nearest available point, the offset showing on the charts.

The contour of the platform is the distinctive feature of a marker that identifies the intermediate block in which it is located. It is desirable that the distinctive types be as few and simple as possible, those recommended being circular, square, triangular, and a trefoil. All markers within an intermediate block are to be of the same contour, and the shape of the platform as viewed or observed from above readily identifies the intermediate block, and the four shapes suffice for the four intermediates that form a quarter section of a major block.

It is necessary that the visibility of the markers be preserved under snow-conditions when the ground and the platforms are white with snow. For this purpose the platforms are made with a skirt or flange around the outer rim or edge sloping outward at a steep angle and preferably painted black. From above this will appear to the

aviator as a black line outlining the edge of the marker. Snow may adhere thereto to some extent on the windward side, after a storm, but sufficient portions will be exposed to catch the eye of the aviator.

70

The quarter-section is preferably to be indicated by an adjunctive instrumentality that will not confuse the platform contour, but which may be readily interpreted, and in a prior presentation of the project, the markers were to be provided with an arm projection to the northwest, the northeast, the southwest or the southeast, as the case might be. An arm projecting out from the rim of a marker will detract from the distinctiveness of the contour and be confusing to the observer, and moreover he might be in doubt as to the compass-direction in which the arm was pointing. It is therefore proposed that the quarter section be indicated by one or more discs, separate and detached from the marker platform, but carried by the platform-structure on a level with the platform.

80

The position of these discs with respect to the platform is immaterial. They will be far enough removed from the platform so that under snow conditions the space between a disc and the platform will not be bridged by the snow and the outline of the platform be broken. One disc may signify the first or northwest quarter of the major block, two discs the second or northeast quarter, three the northwest quarter, and four the southeast quarter; or the absence of any disc may signify the first quarter-section, and one, two or three discs the other quarter-sections.

90

The combination of the four contour outlinings and the discs provides for the ready identification of any one of the 16 intermediate blocks without recourse, on the part of the observer, to compass-directions.

105

With respect to the major-blocks, which represent areas of 200,000 to 300,000 square miles, it is assumed that no marker feature is necessary. An aviator will know his position as between eastern Massachusetts or Ohio, central Illinois or southern Alabama, the north of France or Spain. With this knowledge of the marker-shape and the number of accompanying discs, which will appear as dots or spots contiguous to the platform, he at once knows his position within 2 degrees.

110

The minor-block units as indicated in Figure 2 are indicated by numbers, from 1 to 25, showing in the center of the markers. The numbers are placed to be read from the south and appear separate and detached from the surrounding platform in a central open field. The space between the number and the edge of the surrounding platform will be sufficient, in northern districts, to bar the formation of a snow bridge. To maintain the ready visibility of the numbers

115

120

125

130

under snow-conditions, they are preferably of precipitately sloped steel or metal strips painted black. Though in winter, in some districts, a marker may carry a heavy snow-blanket, there will be open space around the designating number and the lines will be sufficiently exposed to be readily decipherable. An aviator may not be able to read the number from a considerable elevation, but, if knowledge of the intermediate block from the marker contour is not sufficient, he can descend low enough to decipher the number.

A marker located within the confines of a minor block, for example in proximity to a landing field, will show the features called for by that minor block with the addition of an inside ring around the legend or number and a narrow annular space between the ring and the platform. This device will signify that the marker is within the area of the block, the position of the same being shown in the chart for that district.

At the frontier crossing of a posted route, the boundary line may be marked by a split platform of the contour called for by the intermediate block but without a number or character, the platform being divided by a central gap conforming in direction to the boundary line.

As installations are made from time to time, the locations will be published as items of general news and the aviators will mark the locations on their charts. This publication will call simply for the longitude and latitude designation of the major-block, the intermediate block-letter, and the minor block-number. In the case of a marker that is off the true location, its position will be given by coordinates with respect to the block-corner; as, for example, when because of the topography of the country "104-40 D 8" is erected "2 miles north and 3 miles east" of the north-west-corner of said block.

If a continental route is posted on an unbroken east and west, or north and south

line, there will be a duplication of the markers in the major-blocks traversed. For example, if a due east and west trans-continental line be posted from Georgia to California, the series of markers in blocks "80-40," "88-40," "96-40," "104-40," "112-40," "120-40" and "128-40" will be duplications. This can be avoided, in laying out the line, by offsets between major blocks. If at the junction of "80-40" and "88-40" the line be sidestepped to the next tier of minor blocks, say to the north, it will strike a different series of marker numbers; then crossing to "96-40" let there be another offset and likewise with each successive block. There will then be no duplicate marker at any point on the entire line. The same course can be followed with respect to north or south posted lines.

A cordon of markers surrounding an industrial district will give an aviator his bearings from whatever direction he approaches. Knowing the latitude and longitude of a point within a district, the block locations and the proper contour, quarter-section designation, and numbers are readily determinable.

For night service on a route where there is regular travel the markers may be equipped with lights, under radio control, so that an aircraft, with wireless-control-equipment, may, at will, cut in the lights within range, and lights will be on only as needed.

I claim:

An aeronautic chart system, including a marker-instrumentality contoured to have an open central field and adapted to function as an elevated platform, said platform having a distinguishing element arranged and observable within said central open field for indicating a unit of the system.

In witness whereof I hereunto set my hand.

STORY B. LADD.
